C. RASMUSSEN

WOOD SPLITTING MACHINE

Filed Feb. 19, 1926

FIG. 1.

FIG. 2.

FIG. 3.

Inventor
Carl Rasmussen
by Hubert W. Janne,
Attorney.

UNITED STATES PATENT OFFICE.

CARL RASMUSSEN, OF MENLO PARK, CALIFORNIA.

WOOD-SPLITTING MACHINE.

Application filed February 19, 1926. Serial No. 89,364.

This invention relates to machines for splitting logs of timber; and it consists in the novel construction and combination of the parts hereinafter fully described and 5 claimed.

In the drawings, Figure 1 is a front view of a wood splitting machine constructed according to this invention. Fig. 2 is a side view of the same. Fig. 3 is a plan view of 10 the weight and blade, showing the guide bars in cross-section.

Two crossbars 6 are provided, and are supported at one end by a single leg 7, and at the other end by a pair of legs 8 arranged 15 at an angle to each other and provided with braces 9. The tripod frame thus formed has two parallel guide bars 10 suspended from the top crossbars 6, and arranged so that their bottom ends will clear the largest 20 log to be split. A suitably offset brace 12 couples the bottom ends of the two guides together. Guide sheaves 14 are journaled in the frame on suitable pins 15, and a flexible member 16, such as a cord, is supported by these sheaves.

A weight 18 is secured to one end of the cord, and is slideable vertically in the guide bars 10. The sides of the weight are grooved so as to engage with the guide bars, 30 and a sharp blade 20 is secured in a socket in the lower part of the weight. The weight is made of such a length that it does not wholly slide out of the guide bars in the act of splitting a log. Any suitable 35 means is provided for raising the weight,

such as a winch, or a motor, or the cord can be pulled by hand.

The log to be split is placed on the ground under the guide bars when the weight is raised, and the log is split by allowing the 40 weighted blade to fall upon it.

The tripod form of frame gives the machine the necessary stability, and affords free access to the log. The machine is simple and inexpensive to construct, and is 45 not liable to get out of order.

What I claim is:

1. A machine for splitting wood, comprising two substantially horizontal crossbars spaced apart, supports secured to the end 50 portions of the crossbars, two vertical guide bars arranged parallel to each other and suspended from the crossbars between their end portions with the bottom ends of the guide bars clear of the ground, a weighted blade 55 slideable between the guide bars and free to project below their bottom ends when lowered, guide sheaves mounted on the crossbars, and a flexible lifting device supported by the said sheaves and connected to the 60 weighted blade.

2. A machine for splitting wood as set forth in claim 1, the said supports comprising a single leg at one end portion of the crossbars, and a pair of legs at the other end 65 portion, said pair of legs having cross-braces between them.

In testimony whereof I have affixed my signature.

CARL RASMUSSEN.
